UNITED STATES PATENT OFFICE.

ALBERT G. P. DORSEY, OF CLARKSBURG, INDIANA.

CLOTHES-LINE.

SPECIFICATION forming part of Letters Patent No. 336,705, dated February 23, 1886.

Application filed April 10, 1885. Serial No. 161,820. (Model.)

To all whom it may concern:

Be it known that I, ALBERT G. P. DORSEY, of Clarksburg, in the county of Decatur and State of Indiana, have invented a new and 5 Improved Clothes-Line, of which the following is a full, clear, and exact description.

Reference is to be had to the accompanying drawings, forming part of this specification, in which similar letters of reference indicate corresponding parts in all the figures.

Figure 1 is a sectional elevation of my invention. Fig. 2 is a rear elevation of the same, and Fig. 3 is a rear elevation of the compensating-weight removed from the clothes-line.

The invention will first be described in connection with the drawings, and then pointed out in the claims.

Referring to the drawings, A represents a 2c post or other stationary object, provided with the pulley B, over which the clothes-line C passes. The clothes-line C is, by preference, of wire and endless, and, besides passing over the pulley B, passes also over the pulleys D and E, the former of which is made fast upon the crank-shaft F, journaled in the parallel uprights G G. The latter, E, is journaled at the outer end of the horizontal or nearly horizontal arm H, attached to the upper ends of the 3c said uprights G G. The uprights G G are pivoted to the flanges T, attached to the foot piece or plate J, that may be made fast to the floor of the laundry-room. A lever, K, is also pivoted to the flanges T, and this lever is connected to the uprights G by the link or connecting-rod L, for forcing the uprights G backward for drawing the line C taut, and the lever K is provided with the pivoted leg or brace-piece M, for bracing back the uprights G (through the lever K and connecting-rod L) for holding the line taut. To the upper ends of the uprights G is pivoted the bar O, to the outer end of which is pivoted the bar N, which in turn is pivoted to the pointed 4c gathering-arm P, for taking the clothes off from the line C when the crank F is turned to move the line in the direction of the arrow. The arm P has the opening a formed in it for the passage of the line C, so that the point of 5c the arm P stands below the upper portion of the line, as shown in Fig. 1. To the upper side of the arm P is secured the strong wire or rod Q, for gathering the clothes-pins p at the time of taking in the clothes.

In use, to hang out the clothes the same 55 are placed, piece by piece, upon the upper portion of the line C and secured by the clothes-pins p. As each piece is secured, the crank F will be turned to move the line opposite to the arrow. When the line is half full, or when 60 the upper portion of the line begins to sag under the weight of the clothes, the weight R will be run out upon the lower portion of the line, the weight of which counterbalances the weight of the clothes and prevents the upper portion of the line from sagging materially. The clothes having been in this manner all hung out, after they have become dry, to take them in it is only necessary to turn the crank F in the opposite direction, which will 65 cause the clothes-pins first to be detached from the line and strung upon the rod or wire Q. Then the clothes will gather in a bunch upon the arm P, from which they may be taken from time to time. The weight R is 70 slotted at r, so that when the clothes are all placed upon the line the weight may be turned upside down and the upper portion of the line placed in the slot r, so as to attach the upper and lower portions of the line together 75 to make the whole more rigid and to prevent sagging.

It is designed to place the plate J within the laundry-room and the post A in the yard, so that the clothes may both be hung out and 80 taken in without going out of doors.

Having thus described my invention, what I claim as new, and desire to secure by Letters Patent, is—

1. The combination, with the uprights G, of 90 the gathering-arm P, pivotally connected to the upright and the line, as and for the purposes described.

2. The uprights G, having the arm P connected to it by connecting-pieces N O, in combination with the line C, means for supporting the outer end of the line, pulleys E D, and crank-shaft F, the arm P having the passage a formed in it, substantially as described. 95

3. The combination, with the gathering-arm 100 P and the line C, of the rod Q, for gathering the clothes-pins, substantially as described.

ALBERT G. P. DORSEY.
